CLAIM

The ornamental design for an ionising bar, as shown and described.

DESCRIPTION

1. Ionising bar
2. Ionising bar
- 1.1 : Perspective
- 1.2 : Left
- 1.3 : Right
- 1.4 : Front
- 1.5 : Back
- 1.6 : Top
- 1.7 : Bottom
- 1.8 : Cross sectional
- 1.9 : Cross sectional
- 1.10 : Perspective
- 2.1 : Perspective
- 2.2 : Left
- 2.3 : Right
- 2.4 : Front
- 2.5 : Back
- 2.6 : Top
- 2.7 : Bottom
- 2.8 : Cross sectional
- 2.9 : Cross sectional
- 2.10 : Perspective

The ionising bar comprises sharp ion-emitting pins, each being located in a recess in the bar. No claim is made for the parts shown in dashed lines. Contour lines/shading are only used to show the shape/contours of the 3D shape of the
